5 Claims. (Cl. 260—540)

1

This invention relates to the preparation of saturated carboxylic acids and has particular reference to their preparation from tertiary olefins and derived allylic halides.

In petroleum refinery gas streams, particularly those from thermal and catalytic cracking operations, sizable quantities of olefinic compounds are to be found. Of these a major portion usually comprises ethylene and propylene which can be separated and polymerized to form useful products. Another substantial portion consists of tertiary olefins, such as isobutylene and its homologs. A primary object of the present invention is the provision of a process for converting this substantial portion of refinery gas streams to saturated aliphatic carboxylic acids or their salts. Another object of the invention is the provision of a process for producing saturated aliphatic carboxylic acids, particularly within the range of four to about sixteen carbon atoms per molecule. A further object of the invention is the provision of a process for converting halogenated olefins to saturated aliphatic carboxylic acids. The invention has for other objects such other advantages or results as will appear in the specification and claims hereinafter made.

Briefly stated, the present invention comprises the caustic oxidation of a primary allylic halide, preferably the chloride or bromide, in which at least the beta carbon atom (the olefinic carbon atom adjoining the halogen bearing carbon atom) is tertiary, the said oxidation essentially including bringing the halides into contact with a preheated alkali, preferably either sodium or potassium hydroxide. The allylic halides are obtained by halogenating tertiary olefins. The alkali can be preheated to above its melting point so as to provide a liquid oxidizing medium; or preferably, the alkali can be dispersed in an inert oil. When employing the preferred procedure, the suspension is preheated to a temperature between about 175° and 350° C., and preferably between 200° and 300° C. The allylic halide is brought quickly into contact with the alkali at the elevated temperature.

The most surprising aspect of our process is the fact that a saturated carboxylic acid is prepared from an unsaturated halide. The following unusual reaction apparently occurs: the preheated alkali effects an oxidation of the halogen radical, and at the same time a reduction of the olefinic bond of the olefinic halide. It is additionally notable that the halide is directly convertible to the saturated acid without the necessity of any intermediate hydrolyzing step.

2

Yields of potential commercial importance are obtained primarily because of the employment of a rapid heating technique whereby the reactants are brought quickly to the temperature at which the alkali salts are formed. If the reactants are heated slowly to this reaction temperature, side reactions, that take place at lower temperatures and include, for example, the formation of diallylic ether, lower the yields of the desired acid. A convenient and effective method of rapid heating is to heat, to the reaction temperature, a slurry of the alkali in a non-reacting liquid medium such as a neutral oil.

Materials that are useful in the preparation of the saturated carboxylic acids are primary allylic halides in which one olefinic carbon atom is tertiary, in which the halogen radical is in an allylic position and is also primary, and in which the alkyl radicals contain at most about ten carbon atoms per molecule. One relatively simple process for preparing these allylic halides from the tertiary olefins comprehends bringing, for example, chlorine or bromine and the olefins into contact for a very brief reaction period of between about 0.005 to 0.1 second and preferably less than 0.01 second at a temperature between about 65° to 120° C. while maintaining an excess of the olefin equivalent to a ratio of about one mol of olefin to between about 1/2 and 3/4 mol of the halogen. Yields as high as eighty-five percent by weight of the feed stock olefin can be obtained. A plentiful source of the allylic halide is isobutylene which can be chlorinated to form methallyl chloride.

Polymerization of butylene and isobutylene in refinery gas streams yield butylene codimer and diisobutylene of which the former comprises at least thirty to thirty-five percent 2,3,4-trimethyl pentene-1 and the latter seventy-five to eighty percent 2,4,4-trimethyl pentene-1. Other products of butylene polymerization are halogenated in a non-primary position. These compounds degrade by molecular scission during caustic oxidation and are consequently readily separable by fractional distillation from the product acid.

In a preferred method of carrying out the process of invention, the primary allylic chloride or bromide is brought into contact with an alkali essentially free of non-associated water suspended in an inert medium, for example, heavy white oil (a highly refined white mineral oil of technical or medicinal grade having a Saybolt Universal viscosity at 100° F. of between about 175 and 350), at temperatures between about 200° and 300° C. and preferably 225° to 300° C. and at pressures from atmospheric to about 1500 pounds per square

inch gauge. The operating pressure, not highly critical, is generally governed by the vapor pressure of the employed halide at opening temperature.

Agitation of the allylic halide in the caustic-oil suspension improves yields and product quality. Evolution of gas from the reactant effects some agitation. This gas, largely hydrogen, is evolved during the reaction period in the amount of about one mol per mol of allylic halide.

The alkali-metal salt of a saturated carboxylic acid having the same number of carbon atoms as that of the starting allylic halide is formed. The corresponding free acid can be liberated from the reaction mixture by treatment of the latter with strong mineral acids.

Example 1

In an example of our process wherein a preheated alkali is used without an inert oil, 195 grams (3.0 moles) of a commercial potassium hydroxide, that melts at about 160° C., are placed in a stainless steel autoclave equipped with a stirring device. The autoclave was sealed and purged with nitrogen. Nitrogen was pumped into the autoclave to a pressure of 300 pounds per square inch gauge and the contents were heated with agitation to 260° C. A mol (90.6 grams) of methylallyl chloride was pumped into the hot caustic at a rate (about 3 cc. per minute) at which rapid heating of the introduced chloride was accomplished. The mixture was stirred, while maintaining the reaction temperature, for 35 minutes after the chloride addition was completed. The reactor-autoclave was cooled and nitrogen and reaction gas were vented. The reaction mass was dissolved in water, thus providing a solution of product salt, potassium chloride, and unreacted caustic. A yield of 71.8 mol percent of potassium isobutyrate was obtained. No substantial amount of degradation product, either acetate or formate, was detected in the reaction product.

Example 2

In this example, commercial grade methylallyl chloride was employed as the feed stock. This allylic chloride was refractionated, and the fraction that distilled over within the range of 71 to 72° C. was used as feed to the reaction zone.

A preheated suspension of caustic potash was prepared by placing 142 grams or 2.20 mols of potassium hydroxide pellets and 50 cc. of heavy white oil in a stainless steel stirring autoclave, which was then sealed. Nitrogen was introduced to a pressure of 200 pounds per square inch gauge and the mixture was heated with agitation to 260° C. Thereafter a solution of 90.6 grams or 1 mol of methylallyl chloride in 90 cc. of heavy white oil was pumped into the hot caustic mixture at an average 1.1 cc. per minute. A noticeable increase in pressure was observed. The mixture was stirred for one hour following addition of the halide, making a total reaction period of 5 hours. After cooling, the nitrogen and reaction gas, or hydrogen, were vented. 800 cc. of water were added to dissolve potassium isobutyrate, potassium chloride and excess potassium hydroxide. The aqueous solution was separated and freed from neutral oils. The aqueous solution was acidified with sulfuric acid; the organic acid was separated and distilled to give a 73.2 mol percent yield of isobutyric acid having a boiling point of 98° C. at 105 mm. mercury. Other inspections showed

the following: n_D^{20} , 1.3931; d_4^{20} , 0.947; neut. equiv., 88.6. The acid was further characterized through its p-bromophenacyl ester (M. P. 77.5-78.2° C.) which gave no depression of a mixed melting point when mixed with an authentic sample.

Example 3

Powdered potassium hydroxide in the amount of 70.7 grams, or 1.10 mols, was suspended in 150 cc. of heavy white oil in an alkali-resistant reactor, and was heated with agitation to 275° C. Olefinic chloride, that was prepared by the chlorination of diisobutylene and contained approximately 80% of the primary halide, beta-neopentyl allyl chloride, was added dropwise over a period of about two hours and until 73.3 grams, or 0.50 mols, had been added. The reaction mixture was maintained for another two hours at 260° to 275° C. during which time allylic chloride which distilled from the reaction mixture was recycled. During the reaction 0.52 mols of gas were evolved.

The mixture was cooled and 200 cc. of water were added to dissolve the potassium octanoate and potassium chloride. The aqueous solution was separated and freed from neutral oils. The aqueous solution was acidified with sulfuric acid and distilled to give the following fractions:

Fraction	B. P., ° C.	Wt. (gms.)	Neut. Equiv.	Weight Percent on Charge
1.....	60-70° C./10 mm.....	2.6	100.0	3.5
2.....	70-100° C./10 mm.....	0.9	103.0	1.2
3.....	100-104° C./10 mm.....	39.7	144.2 (144.2)	54.2

Upon a basis of 80 percent of primary chloride in the chlorinated diisobutylene, a yield (fraction 3) of 69% of theoretical was obtained. The product, octanoic acid, had the following values: n_D^{20} , 1.4221, sp. gr., 0.891; and Br₂ No. 0.22 gms. Br₂/100 gms. sample, or only 0.2 weight percent of olefin.

Our process has the advantages of being direct, in accomplishing two alterations of the reactant molecule in one step, and in avoiding losses which unavoidably arise from multiple-steps. Heretofore, the conversion of allylic halide to the corresponding saturated carboxylic acid has involved a multiplicity of steps comprising hydrolysis to the allylic alcohol, rearrangement of the allylic alcohol to the saturated aldehyde and finally oxidation of the aldehyde to the acid. Although clearly not equivalent to our process in that an additional step is involved, hydrolyzed allylic halides can be oxidized, preferably by a preheated dispersion of caustic in an inert medium, to obtain the corresponding saturated acid.

Organic carboxylic acids are generally useful as intermediates in organic synthesis. These acids are useful in the preparation of V. I. improvers in lubricating oils, oil additives, plasticizers, solutizers, hydrocarbon thickening agents, cellulose modifiers, varnishes, perfumes, flavors, flavoring agents, emulsifying agents, resins, and detergent compositions.

Having described our invention, we claim:

1. The process of preparing a saturated carboxylic acid directly from a primary allylic halide in which the halogen radical is selected from the group consisting of chlorine and bromine, an olefinic tertiary carbon atom adjoins the halogen-bearing carbon atom and the allylic halide contains a number of carbon atoms per

molecule in the range of 4 to 8, which process comprises heating an alkali metal hydroxide to a temperature in the range of about 200 to 350° C. to provide a hot liquid oxidizing medium, slowly adding said primary allylic halide to said hot liquid oxidizing medium while agitating said medium and maintaining it in said range whereby the primary allylic halide is quickly raised to said temperature with the avoidance of side reactions that would take place at lower temperatures, continuing the agitation of the primary allylic halide in the hot reaction medium until a substantial amount of gas is liberated therefrom evidencing substantial conversion, acidifying the resulting alkali metal saturated carboxylic acid salt and recovering a saturated carboxylic acid from said salt, said carboxylic acid having the same number of carbon atoms per molecule as said allylic halide.

2. The process of claim 1 wherein the hot reaction medium includes a diluent consisting essentially of a heavy refined mineral oil. 20

5 3. The process of claim 1 wherein the primary allylic halide is methallyl chloride and the conversion is effected under superatmospheric pressure.

4. The process of claim 1 wherein the allylic halide is beta-neopentyl allyl chloride.

5. The process of claim 1 in which the conversion temperature is in the range of 225 to 300° C.
